CLAIM

The ornamental design for a 35 mm camera, as shown
and described.

DESCRIPTION

FIG. 1 is a front elevational view of a 35 mm camera
showing my design, with a lens cover in the closed
position;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof; and

FIG. 7 is a front perspective view thereof, with a lens
cover in the open position.

*FIG. 1**FIG. 2**FIG. 3**FIG. 4**FIG. 5**FIG. 6**FIG. 7*
